UNITED STATES PATENT OFFICE.

DAVID GERARD ZWARTZ, OF ARNHEM, NETHERLANDS, ASSIGNOR TO NAAMLOZE VENNOOTSCHAP NEDERLANDSCHE KUNSTZIJDEFABRIK, OF ARNHEM, NETHERLANDS.

MANUFACTURE OF ARTIFICIAL SILK.

No Drawing.

Application filed December 1, 1925. Serial No. 72,597.

To all whom it may concern:

Be it known that I, DAVID GERARD ZWARTZ, a subject of the Queen of the Netherlands, residing at Arnhem, in the 5 Province of Guelderland, the Netherlands, have invented certain new and useful Improvements in the Manufacture of Artificial Silk, of which the following is a specification.

10 The speed of manufacture of artificial silk in a factory producing threads of different denier is impaired by the difficulty of distinguishing the different deniers. After the bleaching and other after-treatments the threads are in the form of skeins which may easily be classed by attaching 15 to them coloured strings. Before the threads have arrived at the form of skeins, however, their differentiation is far from 20 easy.

My invention relates to an improvement in the manufacture of artificial silk which facilitates the keeping apart the threads of different denier during the process of 25 manufacture.

According to my invention the artificial silk during or after the spinning is wholly or in part dyed with a dye which is completely or substantially completely decolorized or removed by the bleaching or by one 30 of the other after-treatments.

Preferably the dye is added to the washing liquor at the end of the washing.

For example, the artificial silk threads of 35 80 denier wound on bobbins are washed in the usual way, and a quantity of methylene blue is added to the last quantity of the washing liquid. The artificial silk is dyed blue and keeps this colour during the following treatments, till the bleaching removes the colour from the threads.

For threads of 100 denier the same operation is performed with a red dye, and so on.

Instead of dyes which are decolorized 45 easily by the bleaching liquid, dyes may be used which are removed or decolorized by the action of one of the other after-treatment baths.

My invention may also be applied in the 50 method of centrifuge spinning. In this case the dye liquor may be applied in atomized condition in the spinning centrifuge, or in some other way.

My invention is particularly applicable in 55 the viscose silk manufacture, without any difficulty or unfavourable effect arising therefrom. But also in the manufacture of artificial silk by the cuprammonium and nitrocellulose processes, my invention is of 60 considerable importance.

It is also possible to add the dye in a separate bath, immediately after spinning, or on completion of the washing. Preferably a dye is used which is completely 65 decolorized by the bleaching liquid. However, dyes may be used which are removed by simple washing with alkaline or acid liquids or even with pure water. In the latter case, the dye and be added only after the washing process has been completed.

I claim:

1. The improvement in the manufacture of artificial silk which consists in facilitating the keeping apart of threads of different 75 denier by wholly or in part dyeing the artificial silk during or after the spinning with a dye which is decolorized or removed completely or substantially completely by the bleaching process or any other after-treatment.

2. The mode of applying the improvement referred to in claim 1 which consists in adding the dye to the washing liquid at the end 80 of the washing.

In testimony whereof I affix my signature.

D. G. ZWARTZ.
